UNITED STATES PATENT OFFICE.

WILLIAM A. KENDRICK, OF YALESVILLE, CONNECTICUT, ASSIGNOR OF ONE-HALF TO CHARLES MADEIRA, OF YALESVILLE, CONNECTICUT.

EGG-OPENER.

SPECIFICATION forming part of Letters Patent No. 691,389, dated January 21, 1902.

Application filed May 6, 1901. Serial No. 58,921. (No model.)

To all whom it may concern:

Be it known that I, WILLIAM A. KENDRICK, a citizen of the United States, residing at Yalesville, in the county of New Haven and State of Connecticut, have invented certain new and useful Improvements in Egg-Openers; and I do declare the following to be a full, clear, and exact description of the invention, such as will enable others skilled in the art to which it applies to make and use the same, reference being had to the accompanying drawings, and to the figures of reference marked thereon, which form a part of this specification.

My invention relates to egg-openers, and has for its object to form an egg-opener composed of two cup-shaped members formed of thin flexible elastic metal or other material having such qualities, whereby the sides may be pressed inwardly by the hand, so as to cause the sides of the cup-shaped members to bear against the egg, said sides resuming their normal shape or position by reason of their elasticity upon removing the pressure of the hand.

It has further for its object to provide an opener composed of two cup-shaped members with elastic puncturing-blades, one of which blades is formed with a double point, the points being spaced apart, so that when the blade is pressed inwardly the two points of the blade will bear against the egg-shell at opposite points of the curved portion of the egg-shell lying between the points, so as to prevent the egg from turning as the puncturing-points are pressed inwardly.

To the accomplishment of the foregoing and such other objects as hereinafter appear, the invention consists in the construction and in the combination of parts hereinafter particularly described and then sought to be clearly defined by the claims, reference being had to the accompanying drawings, forming a part hereof, and in which—

Figure 1 is a side elevation of the egg-opener with the two cup-shaped members closed. Fig. 2 is a vertical section on the line 2 2 of Fig. 1, showing an egg within the device and indicating by dotted lines one side of the two members pressed inwardly against the egg; and Fig. 3 is a side elevation of the

device, showing one of the cup-shaped members raised.

In the drawings the numeral 1 designates two cup-shaped members joined together by a hinge 2 and each of them having a supporting-base 3, so that the device can set with either end up. The cup-shaped members 1 are formed of flexible elastic metal or other equivalent material having such properties, so that if an egg be smaller than the diameter of the cup-shaped members the wall or side of said members may be pressed inwardly by the hand, so as to reduce the cross area of the members and cause the wall to bear against the egg, as indicated by dotted lines in Fig. 65 2 of the drawings. As soon as the pressure of the hand is released the elasticity of the thin flexible metal or other material causes the sides of the cup-shaped members to assume their normal shape. This is of importance, because it avoids the necessity of employing springs inside of the cup-shaped members in order to accommodate eggs of different sizes. These cup-shaped members may be spun or otherwise formed out of thin metal 75 having the properties mentioned.

For the purpose of puncturing the egg-shell so that the shell may be fractured for the purpose of opening the egg I provide two spring-blades 4 and 5, one attached to each 80 of the cup-shaped members, both of which blades are formed with inturned points 6, adapted to puncture the egg-shell when pressed inwardly, said points working in a slot 7, formed at the junction between the two 85 cup-shaped members. In order that the egg may be prevented from turning within the cup-shaped members as the points come in contact with the shell, which sometimes is liable to happen when the blades are pressed 90 inwardly and which when it occurs makes it more difficult to puncture the shell, I form one of the blades 5 with a double point by providing it with two of the inturned points 6, as indicated in Figs. 1 and 3 of the drawings, 95 said points being spaced apart, as there indicated, so that they will lie on opposite sides of the curved portion of the egg-shell fitting between the two points, and thus by gripping the shell at such two points of its curved sur- 100

face the points will serve to prevent the shell from turning, and thus facilitate puncturing the shell by the points of the spring puncturing-blades. As the two blades are arranged as shown in the drawings the single point of one blade will fit between the two points of the other blade, as indicated by Fig. 1 of the drawings, thus facilitating the puncturing of the egg-shell and the separation of the two parts of the shell after being fractured and when the two cup-shaped members are opened.

An egg-opener constructed as described possesses the advantages mentioned and is simple in its construction and efficient in the operation of its parts and ornamental in appearance.

Having described my invention and set forth its merits, what I claim is—

1. An egg-opener consisting of two cup-shaped members hinged together and formed of thin flexible elastic material permitting the sides to be pressed inwardly and adapted to assume their normal shape when the pressure is relieved, and provided with spring

puncturing-blades to fracture an egg-shell, substantially as described.

2. An egg-opener consisting of two cup-shaped members formed each of flexible elastic material provided with puncturing-blades, substantially as described.

3. An egg-opener consisting of two cup-shaped members provided with spring puncturing-blades, one of said blades being double-pointed, the points being spaced apart to permit a portion of an egg-shell to lie between and back of said points, substantially as described.

4. An egg-opener consisting of two cup-shaped members formed of flexible elastic material and provided with puncturing-blades one of which is double-pointed, substantially as described.

In testimony whereof I affix my signature in presence of two witnesses.

WILLIAM A. KENDRICK.
